SPINNING RING

Louis H. Morin, Bronx, N.Y., assignor to Coats & Clark Inc., New York, N.Y., a corporation of Delaware
Filed May 14, 1963, Ser. No. 280,346
1 Claim. (Cl. 57—119)

This invention relates to traveler rings, wherein the body portion of the ring is formed as a die casting in providing a rigid, as well as lightweight body. More particularly, the invention deals with a ring of the character defined, wherein the traveler engaging portions of the ring are covered with a plastic coating, preferably by injection molding of the plastic on said portion of the ring.

The novel features of the invention will be best understood from the following description, when taken together with the accompanying drawing, in which certain embodiments of the invention are disclosed and, in which, the separate parts are designated by suitable reference characters in each of the views and, in which:

FIG. 1 is a plan view of a ring made according to my invention; and

FIG. 2 is an enlarged broken section on the line 2—2 of FIG. 1.

Considering FIG. 2 of the drawing, it will appear that the metallic ring body 10 comprises an inner annular traveler engaging portion 11, the outer surface of which has an annular enlargement 12 centrally thereof terminating at one side in an extending flange portion 13. The portion 11 has annular diverging rims 14 and 15 extending beyond the surfaces of 12, the rim 14 being preferably of less thickness than the rim 15, as clearly noted in FIG. 2 of the drawing. It will also appear that the outer surface of the rim 14 is beveled, as seen at 14'. The body 10 is formed as a die cast product, preferably of aluminum or magnesium to be light in weight.

Applied to the portion 11, including the rims 14 and 15, is a shell coating 16 of suitable plastic material. In applying this coating in accordance with one method of producing the end product, the coating 16 is injection molded onto the portion 11, including the rims 14 and 15, by the use of such plastic materials as nylon, Delrin, Celcon or fluorocarbons, such as Teflon and Kel-F, to provide on the portion 11 and rims 14 and 15 a smooth wearing surface, upon which the travelers operate.

2

Production of traveler rings in accordance with the structure above defined will not only result in producing a lightweight, economical and, yet, strong and durable structure, but will also obviate the necessity of lubrication of a ring or the need for cleaning, buffing or otherwise processing metal rings, as commonly employed.

By virtue of the cross-sectional contour of the ring, as clearly noted in FIG. 2 of the drawing, it will be apparent that the metallic rigid body portion of the ring can be readily die cast and, further, the shell plastic coating 16 can be easily applied by reason of the coating having what may be defined as ring portions 16' and 16", which are hook-shaped in cross-sectional form and which envelop the rims 14 and 15, leaving 12 and the flange 13 uncovered or uncoated.

Having fully described my invention, what I claim as new and desire to secure by Letters Patent is:

A traveler ring of the character defined, said ring comprising a metallic ring body having a flanged large diameter central portion and an inner annular traveler engaging portion terminating in side rims, said side rims extending from said flanged large diameter central portion, one of said rims being thicker adjacent the said large diameter central portion than at its edge remote 20 from said central portion and an injection molded shell-like coating of plastic material completely enveloping the traveler engaging portion and the rims thereof.
